SHIPPING CASE SETTING-UP AND POSITIONING APPARATUS

Edgar Arrell, Middletown, Kaye B. Holstebro, Gildersleeve, and Mitchell S. Wozniak, Portland, Conn., assignors to Emhart Manufacturing Company, a corporation of Delaware

Application December 28, 1955, Serial No. 555,856

36 Claims. (Cl. 53—186)

This invention relates to machines for automatically opening and squaring-out collapsed or flattened cases or cartons, that is to say, shipping cases "in the flat" as they come from the manufacturer, folding certain of the side and end wall extensions or "flaps" to form the bottom of the case, and then positioning the case on a suitable support or holding member, more especially the funnel or packing chute of a case filling or packing mechanism, and thereafter removing the filled case and delivering it in upright position on an endless conveyor, or other desired support.

It is customary to ship or store containers such as cans of food, beverages and other products, as well as rectangular packages containing cereals, confectionery and the like, and articles such as cakes of soap, etc., in heavy cases or cartons constructed of corrugated board, fibre board, and the like. When the food, beverage or other product is packed in cans, after the cans are filled and closed, it is common practice to deliver them by means of a conveyor to a labelling machine, thence to the packing machine by which the cans are placed in the shipping cases. In this machine the filled cases are conveyed to a case sealing machine which closes and permanently seals the flaps forming the bottom and top of each case so that the cases are ready for storage or shipment. Case packing machines, sealing machines and labelling machines have now been developed to have a speed of operation such that it is impracticable for the collapsed shipping cases to be opened up and placed on the funnel of the packing machine by hand.

Accordingly, the general object of the present invention is to provide a machine for opening up the shipping cases from the flat, appropriately folding their flaps, placing them on the funnel and removing them therefrom, at a rate which is substantially greater than is possible by hand feeding of the cases to the packer.

Another object of the invention is to provide a machine of this kind which will operate without marring or in any way damaging the shipping cases, and which will operate for long periods of time without attention other than the maintenance of an adequate supply of the collapsed shipping cases in the magazine of the machine.

Another, and a particular, object of the invention is to provide an apparatus of this kind which will operate quietly.

A further object of the present invention is to provide a machine of this type wherein the supply of collapsed cases in the magazine can be readily replenished with a minimum of effort on the part of the operator, and without interfering with the proper feeding of the collapsed cases.

A still further object of the present invention is to provide a machine for opening or squaring-out the cases which is positive in its operation so that such cases will be properly opened and squared-out substantially without failure.

The invention will now be described in detail in connection with a machine for opening and folding the flaps

2

of a single tier case which receives a single tier of cans from a can packing mechanism and is illustrated, by way of example, in the accompanying drawings. It will be understood, however, that both the can packing mechanism and the unfolding and positioning mechanism can be adjusted to pack not only a single tier, but two, three or more tiers if required.

In these drawings:

Fig. 26 is a detail vertical section taken on line 26—26 of Fig. 5;

Fig. 27 is a vertical section taken on lines 27—27 of Figs. 5 and 6 showing the mechanism for pushing the empty carton onto the funnel of the packing mechanism;

Fig. 28 is a view in elevation looking towards the right end of the apparatus as shown in Fig. 5, showing the drop-off mechanism in upright position;

Fig. 29 is a view similar to Fig. 28 but with the parts shown at the completion of the drop off movement;

Fig. 30 is an elevation of the parts shown in Fig. 29 looking from the right;

Fig. 31 is a detail horizontal section taken on line 31—31 of Fig. 29;

Fig. 32 is an elevation, with parts shown in section, of the lower case blank feed mechanism shown in Fig. 3 and drawn to an enlarged scale;

Figs. 33, 33a and 34 are detail vertical sections of the blank feed mechanism, Fig. 33 being taken on line 33—33 of Fig. 34 and Fig. 34 on line 34—34 of Fig. 33, while Fig. 33a shows some of the parts of Fig. 33 in different positions;

Fig. 35 is a transverse vertical section taken on line 35—35 of Fig. 32 showing parts of the feed mechanism;

Fig. 36 is a vertical section taken on line 36—36 of Fig. 35 with the feed latches in released position; and

Fig. 37 is a timing diagram.

General statement

A brief description of the apparatus and its operation will first be given. Referring to Figs. 1 to 6, the machine comprises three principal sections, namely a collapsed case magazine and opening section, indicated generally at 1, a case positioning section indicated generally by reference numeral 2, and a packing mechanism section indicated generally by reference numeral 3. The magazine section is arranged to contain a group or supply 4 of case or carton blanks, that is, collapsed or flattened cases. These are made, as stated above of heavy corrugated board, fibre board or the like. The weight of the products to be placed in the cases is substantial, as is indicated by the fact that the machine that is to be described is intended to pack twenty-four twelve ounce cans. When a plurality of tiers are inserted the weight is increased accordingly.

The case blanks or collapsed cases in the supply 4 are completely formed with side and end walls and top and bottom extensions (usually referred to as flaps) which are foldable to form the top and bottom of the case. In other words, each blank is a complete case "in the flat" and requires only to be squared out into rectangular form and have the flaps thereof folded properly and glued in order to form a shipping case. These case blanks, or collapsed cases, are edgewise mounted in the magazine section in a compact group with their flaps extending horizontally.

The blanks are supported on one of the folded or rounded edges of the case or box body portions which rest upon a stationary horizontal slideway or bed 5 and slide toward the right of Figure 1 under the action of upper and lower pairs of feed members 6 which are actuated by mechanism, to be hereinafter described, which moves the blanks along the bed 5 to the squaring-out mechanism arranged on the right-hand end of the magazine section 1.

Heretofore in machines for squaring-out flattened or collapsed cases, the case blank has been opened up and the necessary flaps folded to form, for example, the bottom of the case, at a single station. Also the thus pre-

pared case was then pushed onto the funnel of a packing machine, and the packing mechanism itself pushed the case off of the funnel after the insertion of the contents, and, while the filled case was still opposite the funnel lowered the case, turning it to upright position and depositing it on a support, such as a conveyor.

In the present machine, however, these operations, instead of being carried out at two stations, are partially carried out at each of four stations. These four stations 10 comprise the case opening or squaring-out station A, the flap folding station B, the packing station C, and the drop-off station D. By carrying out the various operations at a larger number of stations, there is less idle time for various parts of the mechanism during the step-by-step advancing or feeding of the squared-out case, and this contributes to a larger production rate or speed of operation.

In addition, the prior machines feed the case blanks laterally, one at a time, from the bottom of an upright 20 stack or supply of collapsed cases and to the single squaring-cut and flap folding station. But in the present machine the stack of blanks is laid on its side to form the group or supply 4 of edgewise supported blanks and the blanks are opened up and squared-out from one end of 25 such horizontal stack or group.

The cases are successively opened at station A and 30 progress through stations B, C and D, above referred to. The drop-off mechanism at station D deposits them in upright position near the end of an endless conveyor 7.

35 This conveyor usually moves the filled cases to a carton closing and sealing apparatus by which the flaps at the bottoms and tops of the cases have adhesive applied thereto and are then folded, or re-folded, into closed position and sealed ready for shipment or storage.

35 The cases are advanced intermittently from station to station by means of a reciprocating carriage to be described later on. The three cases are momentarily stationary at stations B, C and D, while the reciprocating carriage makes its return stroke.

40 At station or position A this carriage cooperates with mechanism shown at the right end of the magazine section 1 in removing the squared-out case. The mechanism at the end of magazine section 1 swings the case to partially squared-out position, as shown by the dot and dash lines in Fig. 4. Then grippers on the reciprocating carriage grip the opposite lower flaps of the case and pull it forward, stripping it from the end of the supply or horizontal stack of collapsed cases in the magazine and advancing the case to flap-folding station B. The case is not completely squared-out until the upper front corner of the case is moved against a stop plate at this position. Thus, it will be seen that the complete squaring-out operation is accomplished partly by the mechanism on magazine 1 and partly by the mechanism of the case opening and positioning section 2.

General construction

The construction and operation of the mechanisms at the four stations referred to will be described in detail 60 after describing the basic parts of the apparatus.

Each of the two main sections, that is the magazine section 1 and the opening and positioning section 2, has its own frame structure. The frame structure at the lower right end of the magazine section comprises front and rear cast supporting members 8 (Figs. 1, 4 and 12) which are joined together and held in spaced relation by three cross-bars or rods 9. These frame members support the right end of magazine section 1. The various parts of the case opening and positioning section 2 are supported on front and rear pairs of pedestals 10 and 11 (Figs. 1 and 5) which are joined together by cross and longitudinal members. The parts are carried on two cross rods 12 and 13 secured near the tops of pedestals 10 and 11 respectively, as will be referred to later on. The arrangement is such that this mechanism is inclined

upwardly from case opening position A to the drop-off position D.

The machine, as a whole, aside from the packing mechanism 3 is driven by an electric motor 14 (Fig. 13) which, as indicated, is belt-connected to the input shaft 15 of a speed reducer 16. The out-put shaft of this mechanism is indicated at 17 and is a cross-shaft carrying a series of cams for actuating parts of the case opening mechanism. Shaft 17 extends through the rear supporting member 8 and is journalled in two pairs of anti-friction bearings. One pair 18 of such bearings is shown in Fig. 12 mounted in a rear frame member 19 which is secured in fixed position on the three cross-rods 9. The second pair 18 of such bearings (not visible) is mounted in a similar frame member 19 disposed near the front side of the machine. Shaft 17 is prevented from endwise movement by means of the rear pair of bearings 18, and the inner races of the front pair of bearings 18 are arranged to slide on shaft 17 so that the front frame member 19 may be adjusted widthwise to accommodate case blanks of different height, as will be referred to below.

Driven by cross cam shaft 17 is a longitudinal cam shaft 20 which extends lengthwise of the case opening and positioning section 2. These two shafts operate at the same rotational speed. To interconnect them a short lengthwise shaft 21 is driven by bevel gearing 22 from cross cam shaft 17 and at its right end this shaft, in turn, drives a short cross wise shaft 23 through bevel gearing 24. A third set of bevel gearing 25 drives the lengthwise cam shaft 20. This arrangement is to permit crosswise shifting or adjustment of cam shaft 20, as will be referred to presently, in order to accommodate cases of different height. It will be understood that cross shaft 23 is connected with a slideable key to the bevel gearing 24.

The main frame members of the case opening and positioning section 2 comprises two thick steel plates 26 and 27 (Figure 17) of similar thickness and width and edgewise mounted in spaced parallel relation. Frame plate 26 is mounted in stationary position, while frame plate 27 is adjustable widthwise of the apparatus, that is, with respect to its distance from stationary plate 26. Stationary plate 26 is mounted in any suitable manner near its opposite ends on the two round cross rods 12 and 13 (Figure 5). Cross rod 28 is fixed at its opposite ends to the pedestals 10 and cross rod 13 to the pedestals 11.

Adjustable frame plate 27 is mounted on a sleeve 30 which is arranged to slide on cross rod 12 (Fig. 7). This construction is similar for cross rod 13. Both rods have screw-threaded sections 31 (Figure 7) and each section has a nut 32 with sprocket teeth on its outer periphery. Each of these sprocket nuts 32 is closely engaged on opposite sides by a structure 33 which is secured to the side of frame plate 27. An endless chain 34 (Figs. 5 and 7) passes around the two sprocket nuts 32 and a driving sprocket 35, is arranged for rotation at the lower end of a bracket 36. Sprocket 35 is keyed to a short shaft 37 on the front end of which there is a crank or operating handle 38. By turning this handle the sprocket nuts 32 are simultaneously rotated and cause the frame plate 27 to travel away from or toward the stationary plate 26. As shown in Fig. 7 these two plates are in their closest position where the apparatus is set to handle the minimum height of shipping case.

In addition to bracket 36, a number of other brackets, 39, 40, 41, 42, 43, 44 and 45 (Figs. 5 and 6), are fixed to the outer surface of the movable frame plate 27. These brackets support the lengthwise cam shaft 20 and various other parts to be referred to later. All such parts are simultaneously adjusted in position by the operation of handcrank 38 and adjusting chain 34.

The cases in the positioning section 2 rest upon a pair of rails, 46 and 47, which extend from a point close to the magazine section 1 to the right end portion of the machine. Rail 46 (at the rear) is stationary and extends through the drop-off position D (Figure 6). The

adjustable rail 47, however, terminates short of the drop-off position. Each of these rails has a narrow horizontal portion (Figure 7) on which the body or central part of the case rests.

- 5 The rails also have sloping outer portions to permit the downward bending of the flaps, as indicated, for example, in Fig. 7. Such downwardly bent outer rail portion extends the full length of stationary rail 46, whereas such portion of rail 47 terminates at the left 10 of the packing station C (Figure 6) so as to leave the remainder of the rail 48 horizontal throughout its width in order more adequately to support the filled case at the packing station C and as it is moved to the right to drop-off position D.
- 15 The rear or stationary rail 46 is supported by suitable brackets mounted on the stationary frame plate 26, one such bracket being shown at 49 in Figs. 6, 17 and 19. The movable case rail 47 is similarly supported on movable frame plate 27, one of its supporting brackets 20 being shown at 50, Figs. 4, 5, 6 and 17.

The reciprocating carriage—Case feeding

The reciprocating carriage which has the grippers, previously mentioned, to pull the case at station A forward after it has been opened at the end of the supply 4 in the magazine, and which advances the squared-out cases successively to positions B, C and D, is indicated generally at 51 (see particularly Figs. 7, 17 and 19). Carriage 51 comprises a vertical plate member having downwardly 25 converging end edges, as shown in Fig. 19. At its upper edge the carriage has two supporting rollers 52 which travel upon a rail 53 of semicircular section (Figure 7) and which is secured along the upper edge of stationary frame plate 26. A single similar roller 54 is mounted 30 at the apex of the converging lower edges of the carriage and travels along a second semicircular lower rail 53 which is secured along the bottom edge of plate 26.

Carriage 51 has mounted at its left end the two pairs 40 of grippers, previously referred to, and which are indicated generally by 55 (see particularly Figure 17). It also carries two pivoted case pushers 56 and 57 (Fig. 19). Grippers 55 pull the newly opened case at station A up to station B, and, simultaneously, pushers 56 and 57 respectively advance a previously opened case from 45 station B to station C, and a filled case from station C to drop-off station D, as will presently be more fully described.

Pusher 56 is pivoted on a cross-rod 58 (Figure 17) which is mounted in a pair of brackets 59, one on each 50 side of the machine. Brackets 59 are bolted to a cross-plate 60, suitably mounted crosswise at the top of the vertical plate which is the principal member of carriage 51 (Figure 7). Pusher 57 (Figure 19) pivots on a second cross-rod 61 which is mounted on carriage 51, 55 near its right end.

Each of these pushers has two spaced arms supporting a relatively wide head, as shown in Figure 17, to push the case forward in a straight line, and each pusher is partially counter-balanced by an adjustable weight 62. 60 On the return stroke of carriage 51, it will be understood that the pushers engaging the bottoms of the cases at stations B and C are swung downwardly and slide beneath these cases, swinging up again in front of them ready to push them forward on the next stroke of the carriage 65 towards the right.

The carriage 51 is reciprocated by means of an endless chain 63 (Figure 19) which is trained around to spaced sprockets 64 and 65. Sprocket 65 is an idler sprocket turning on a stud shaft 66 (Figure 17) projecting from 70 the inside surface of stationary frame plate 26. Sprocket 64 is the driving sprocket and drives chain 63 continuously, as will presently be described. The connection between the chain and carriage 51 is a roller 67 carried on the end of a pin which projects laterally from one side of chain 63. Roller 67 is received within a vertical

slot 68 cut in the carriage plate 51 (Figure 19). Hence, as the chain 63 moves around its supporting sprockets, carriage 51 is caused to reciprocate. The carriage travel is the distance between the outer peripheries of these sprockets.

The driving sprocket 64 (Figure 17) is mounted on a short shaft 69 which passes through frame plate 26 and is mounted for rotation in a bearing bracket 70 carried on the outer surface of this plate. At the outer end of shaft 69 a sprocket 71 is keyed which is driven by means of an endless chain 72 from a sprocket 73 which is fixed on cross-shaft 23.

Grippers 55 each comprise a stationary jaw 74 and a movable jaw 75 (see particularly Figs. 17 and 18, Fig. 18 being a view from the rear of Fig. 17). The fixed jaws 74 are formed as portions of the respective brackets 59, while the movable jaws 75 are formed on the ends of reversely curved arms 76 (Figure 7) which are thus formed in order to extend around the ends of the flaps which they grip. Jaws 75 have hub portions 77 that are fixed near the opposite ends of a cross rock shaft 78 (Figure 17).

The shaft 78 is actuated to move the jaws 75, for the purpose of closing and opening grippers 55, by means of an arm 79 having a roller 80 at its outer end (Figure 18). This arm fits loosely on shaft 78 and is connected with a second arm 81 which is fixed to shaft 78. Such connection is by means of a pair of screws and nuts 82 which provide a means for adjusting the clamping pressure exerted between the jaws 75 and 74.

The timing of the closing and opening of the grippers 55 is accomplished by means of a cam 83 (Figure 18) and the associated parts shown in Figs. 18 and 17. This cam turns loosely on a short stud shaft 84 which projects laterally from the rear of frame member 26 (Figure 17). Cam 83 has a hub 85 on which is mounted a sprocket 86 by which the cam is driven through an endless chain 87 from a sprocket 88 fixed to a horizontal shaft 89 that is arranged below and slightly to the left of flap folding station B. Shaft 89 in turn is driven by means of an endless chain 90 from a sprocket 91 on cross-shaft 23, this latter sprocket being arranged preferably on the same hub with sprocket 73.

Associated with the gripper controlling cam 83 (Figure 18) is an arm 92 pivoted at 93 on the side of frame plate 26. The tail portion of arm 92 is provided at 93 with a cam follower roller 94 which rolls on the edge of cam 83. A tension coil spring 95 maintains the roller 94 in engagement with the cam thereby raising arm 92 to the dotted position of Fig. 18 when the roller 94 is on the low portion of the cam.

In this position of arm 92 (shown dotted in Figure 18) it is ready to receive beneath it the roller 80 on gripper actuating arm 79 when the carriage 51 reaches the limit of its forward stroke. This stroke limit is slightly to the left of the position in which the carriage is shown in Fig. 18 (to the right in Figs. 17 and 19), the carriage being shown just after it has begun to move on its back stroke.

During the travel of the carriage from left to right the grippers 55 are held in closed position by means of a coil spring 97 on rock shaft 78. This position is shown in dotted lines in Figs. 7 and 18. When the carriage reaches the end of its right-hand stroke, roller 94 rides up on the outer section of cam 83, thus swinging arm 92 downward from the dotted to the full line position (Figure 18).

This moves roller 80 on gripper actuating arm 79 downward and tucks it under the end of a horizontal rail member 96 which is mounted on studs 98 in slightly spaced relation to the outside of frame member 26 (Figure 17). This is a bar of nearly square cross-section along the under surface of which the roller 80 rides, thereby holding the movable jaws 75 of the grippers in open position during the return stroke of carriage 51.

At the end of such return stroke the roller 80 leaves the left end of rail 96 and the gripper jaws are allowed to close under the action of the spring 97.

5 Sequence in opening and squaring-out the case

Referring to Figs. 8 to 11b, there is shown in Fig. 8 a collapsed shipping case or un-opened case blank 99, as received from the manufacturer in flat, folded condition. This is the foremost blank in the horizontal stack or supply 4 (Figure 4). The second case blank in this supply is indicated by numeral 100. Although the apparatus will handle square cases, the case blanks shown have major and minor side portions 101 and 102. The former are to form the side walls of the case and the latter the end walls, and these four walls constitute the case body. These walls have corresponding extensions or flaps 103, 104, and 103a and 104a, on the near side in Figs. 8-11a, which are to form the bottom of the case as it is deposited on conveyor 7 (see Figure 11b). Flaps 103, 104, and 103a and 104a, at the far side, when folded, form the top of the case.

In Fig. 9 the collapsed case 99 has been partially opened, and in Fig. 11a is almost completely opened or squared-out, by bending the material of the sides at the creases or score lines 105, which are provided at the corners. The flaps 104 and 104a which are extensions of the minor side walls 102 are folded to closed position first and will be referred to as the inner bottom flaps (Figure 11b), while the flaps 103 and 103a which are closed over them will be referred to as the outer bottom flaps.

The mechanism for partially opening certain flaps, squaring-out and picking off the foremost blank from the stack or supply 4 comprises two fingers, a vacuum arm, and a case opening arm carrying a swinging finger or "semaphore" near its upper end, all of which are duplicated on the opposite side of the magazine section 1, one set of these parts operating upon the lower flaps of the case (those on the near side in Figures 8-11a), and the other section on the upper flaps (those on the far side). These parts are shown diagrammatically in Figs. 8-11a. They are also shown in Figs. 4 and 12 as they actually appear in the machine.

These parts, on each side, comprise lower and upper stack-holding or stack-retaining fingers 106 and 107, vacuum cups 108 which are carried on vacuum arms 109, opening arms 110, and opening fingers or semaphores 111. It will be understood that these parts are the same on both sides of the machine, and that they are operated simultaneously.

The two sets of retaining fingers 106 and 107 operate alternately, that is the lower fingers swing outward with a substantial 90° motion, while the upper fingers 107 swing inwardly. At the commencement of the opening cycle the lower fingers 106 are in their open position shown in Fig. 8, in which position the outer or side wall flaps 103 and 103a are free to be swung outwardly about their score lines. Suction is applied to the vacuum cups 108 and the vacuum arms 109 are turned on their vertical axes to the position shown in Fig. 8a until the flaps stand at about 30° to the plane of the case blank. Also at the beginning of the cycle the opening arms 110 are swinging upwardly, as indicated by the arrows in Fig. 8.

As soon as the vacuum cups have turned the flaps to the 30° position, arms 110 reach the vertical position (Figure 8a), and the swinging fingers or semaphores 111 are then swung from the vertical position in alignment with arms 110 to horizontal position at right angles thereto. In Fig. 8a, these arms are approaching such horizontal position where their inner ends extend somewhat behind the case major side portion 101 near the top thereof.

The fingers 106 have now returned to their inner position (Figure 9) and simultaneously the upper stack-retaining fingers 107 have swung to their outer position

thereby releasing the inner or end wall flaps 104 and 104_a and the entire upper portion of the case blank. This allows the arms 110 to swing outwardly and downwardly as they are moving in Fig. 9, to the position of Fig. 10, thereby squaring out or partially squaring-out the collapsed case blank. During this operation the rear or left end wall of the case blank is held against the stack 4 by means of the lower retaining fingers 106.

When the squared-out case has reached the position shown in Fig. 10, the lower side wall 101 is in contact with the case-supporting rails 46 and 47, which are not horizontal, but slant upwardly towards the right (Figures 4 and 5). This prevents the case from being completely squared-out. Prior to this squaring-out movement by the swinging of arms 110, the vacuum arms 109 are swung upwardly and outwardly to the dotted position shown in Fig. 4, so as to clear the outer corner of the case during the squaring-out movement.

As the opening arms 110 reach the limit of their downward movement (Figure 10) the grippers 55 on carriage 51 are approaching the case with their jaws in open position. Shortly thereafter carriage 51 reaches the left-hand limit of its movement and grippers 55 have passed the forward edges of flaps 103 and 103_a (Figure 11). At this point the jaws of the grippers are closed by the mechanism previously described in connection with Figs. 17 and 18, which involves the dropping-off of the roller 80 from the left-end of rail 96 (Figure 17).

The carriage 51 immediately commences its feeding stroke toward the right, and, through the grippers 55, drags or pulls the case free of the stack or supply 4. At the same time, or slightly before this, the lower-retaining fingers 106 commence another outward swinging movement, as indicated in Fig. 11a, thereby allowing the flaps 104_a and 104_{ta} to be released.

As soon as the partially squared-out blank or case 99 is free of the stack it may, and usually does, partly recollapse because of its resiliency, but it remains partially open and is completely squared-out by the engagement of its upper forward leading corner (Figure 4) with a stationary circular stop plate 113 (Figure 1) which is located at the right side of flap-folding station B. As the case arrives at this position, a pair of spring-actuated pivoted holders 114 (Figures 5 and 19) spring upwardly behind the case and hold the case at this position. At about the same time the jaws of grippers 55 are opened by the mechanism previously mentioned (Figures 17 and 18), releasing the case flaps, and carriage 51 begins a return stroke.

Early in the advance of carriage 51 opening arms 110 return to their vertical position, and the vacuum arms 109 turn the flaps 103 and 103_a of the succeeding case blank 100 to the 30° position. The semaphore fingers 111 which were swung downwardly in line with their supporting arms 110, so as to allow the grippers 55 to remove case 99, now return to horizontal position. The arms 110 again commence to move downward, unfolding the next case 100.

As the leading corner of each case engages stop plate 113, the upper surface of the case body is pressed against a pair of resiliently mounted pressure strips 115 (Figures 5 and 7) which extend from position A through packing station C. These light metal strips are suspended by a series of spaced pins from two rigid bars 116 of the same length. Bars 116 are supported on two cross-bars 117 which rest upon upward extensions 118 from the two pedestals 10 and from brackets at the top of pedestals 11. Coil springs 119 are arranged on the spaced pins which support the strips 115 and provide a light downward pressure on the strips and, in turn, on the cases as they are moved along the rails 46, 47 throughout the stations B and C.

Station A—the case opening mechanism

The mechanism for operating the stack-holding or re-

taining fingers 106, 107, vacuum arms 109, and the opening arms 110 together with their opening fingers or semaphores 111 will now be described. This mechanism is shown in Figs. 4 and 12 to 16.

5 Resting upon and secured to the front and rear frame members 19 are two upright frame members 120 which support a part of the case opening mechanism and which also support the superstructure of magazine section 1 which will be described in detail later on. These upright members are secured to frame member 19 by bolts 121 (Figure 13). The mechanism for operating the lower and upper fingers 106, 107 is the same on both sides of the machine, that is, at the front and at the rear. Also the mechanism for operating the two front and rear 15 vacuum arms 109 is identical, as well as the mechanism for operating the rear opening arms 110. Consequently, only the front mechanism will be described in each case, it being understood that the mechanism is duplicated at the rear side of the machine.

20 Referring to Fig. 12 the upper stack-retaining finger 107 is secured to a vertical shaft 122 and the lower finger 106 to a sleeve shaft 123 surrounding approximately the lower half of shaft 122 (also Figs. 13 and 15). The upper end of shaft 122 is journaled for rocking movement in a forward projection of the upright frame member 120, and the lower end portion of sleeve 123 is similarly journaled in front frame member 19. The rocking movement of shaft 122 and upper finger 107 is imparted thereto by means of a cam 124 having a cam track 25 which actuates a cam follower roller 125 which projects to the right from an L-shaped arm 126 which is fixed to the lower end of shaft 122 (Figures 12 and 13).

The lower stack-retaining finger 106 and its sleeve shaft 123 are operated by a somewhat similar cam 127 30 having a track within which a second follower roller 128 is received. This roller projects from a collar 129 which is keyed to the lower end of sleeve shaft 123. These two cams 124 and 127 are keyed to cross cam shaft 17, and it will be understood that their cam tracks are so arranged 35 as to cause the fingers 106 and 107 to be actuated, as previously described in connection with Figs. 8-11b inclusive.

The timing of the actuation of these fingers, as well as of all other principal parts of the machine is shown 40 in Fig. 37.

45 The mechanism for operating the vacuum arms 109 which support the vacuum cups 108, is shown in Figs. 4, 12 and 14. These arms have a compound movement, that is, they are first turned about an offset vertical axis to open the flaps to an approximately 30° position, as 50 shown in Figs. 4 and 14, and thereafter the arms are swung about a horizontal axis to the dotted position so as to be out of the path of the case as it is squared-out. For this reason arms 109 are each secured to a short upright shaft 130 (Figures 5, 12 and 14), one of which is 55 shown in vertical section and which is mounted for turning movement in a head member 131 formed integrally with the inner end portion of a hollow horizontal shaft 132, itself mounted for rocking movement in an elongated bearing housing at the outer end of upright frame member 120.

60 In order to impart the 30° rocking movement to vertical shaft 130 this shaft is provided with an integral pinion 134 whose teeth mesh with a series of circular teeth 135 (Figs. 12 and 14) formed in the surface of 65 and extending substantially throughout the length of a circular rack bar or rod 136 which is mounted for endwise sliding movement within hollow shaft 132. In order to shift this rack member lengthwise and thus cause the angular movement of vacuum arm 109, a bell-crank 70 lever 137 is pivoted at 138 in a bracket extending below housing 133, and having vertical and horizontal arms.

The bell crank vertical arm 139 is provided with a series of arcuate teeth which mesh with the circular teeth 135 near the outer end of round rack bar 136. The horizontal arm of bellcrank 137 is connected to an actuat-

ing rod 140 whose lower end is pivoted to an arm 141 (Figure 13) which is keyed to the outer end of a rock shaft 142. The inner end of this shaft has pivoted to it another arm 143 carrying a roller 144 which is received within the track of a cam 145 (Figure 4) on shaft 17.

In order to impart upward swinging movement to the vacuum arms 109 about their horizontal axes, an operating arm 146 is fixed to the outer end of each hollow shaft 132 (Figures 12 and 14). An operating rod 147 is pivoted at its upper end to this arm and at its lower end to the inner arm of a double armed member 148 (Figure 13) which has a hub 149 common to the two arms and is pivoted for free movement on the outer end of shaft 142. A cam follower roller 150 projects inward from the outer arm of member 148 and engages the track of a cam 151, also mounted on shaft 17.

It will be understood that the two cams 145 and 151 impart the compound turning and swinging movement to the rear vacuum arm 109, these movements being timed with relation to each other and to the movements of the other parts of the opening mechanism, as described in connection with Figs. 8 to 11b, all as shown in timing diagram, Fig. 37. It will also be understood that the mechanism for operating the front vacuum arm 109 is similar to that just described.

The vacuum cups 103 are connected through passages extending lengthwise of arms 109 and flexible hose connections 151a to a solenoid-operated air valve 151b (Figure 1) and thence to a suitable source such as a vacuum pump (not shown). The vacuum valve 151b is controlled by means of a cam-operated switch 151c and a cam 151d on shaft 17 which is arranged to open and close the valve and apply the vacuum in accordance with the timing diagram shown in Fig. 37. Conventional wiring (not shown) interconnects switch 151c, valve 151b, and a power source.

The construction and operation of the front and rear opening arms 110 each carrying a case-engaging finger or semaphore 111 is shown particularly in Fig. 15 and also in Figs. 4, 12 and 13. Rear arm 110 will be described in detail. It is a hollow member and carries within it a rack bar 152 to actuate semaphore 111. Arm 110 has a horizontal pivot mounting close to the vertical side edges of the collapsed case 99 at the left end of the stack or supply 4 and is also mounted in such manner as to pivot approximately in alignment with the lower edge of this collapsed case.

For this purpose arm 110 is mounted on an L-shaped projection 153 (Figure 12) at the inner end of a short horizontal shaft 154 which is suitably mounted in bearings at the top of a frame member 8a located between frame members 8 and 19, the axis of shaft 154 being located approximately in alignment with one of the folded edges, in this instance, the lower edge, of the case blank 99 at the front of the stack. In order to facilitate assembly of the parts, the lower end of arm 110 is held in a clamp 155 arranged at the upper end of projection 153.

In order to swing arm 110 from the vertical position shown in Figs. 4 and 15 to the case squaring-out position indicated diagrammatically in Fig. 10, the inner end portion of shaft 154 is provided with pinion teeth 156 which engage the teeth of a gear sector 157 mounted for rocking movement on a horizontal shaft 158 carried by frame member 8a. Projecting from the same hub with sector 157 there is an arm 159 carrying a cam follower roller 160 which travels within the track of a cam 161—another cam keyed to shaft 17.

The opening finger or semaphore 111 projects from and is preferably integral with the inner end of a very short shaft 162 (Fig. 15) which is mounted for rotation in a housing 163 formed near the outer end of hollow arm 110. This shaft 162 is provided with pinion teeth 164 which engage the teeth of the rack member 152 for the purpose of swinging the semaphore 111 from vertical

position in alignment with arm 110, to horizontal position, as shown dotted in Fig. 12, to engage the case to be opened. Lengthwise movement of rack 152 is brought about by means of a double track arcuate cam structure 165 (Figures 12 and 15), and by means of a compression coil spring 166 which surrounds the lower end of rack member 152, and also by a cam formation 167 on the lower surface of upper case-retaining finger 107. A cam follower roller 168 projects from the outer side of rack 152 near its lower end through a slot in the side of arm 110 (Figure 12).

When the arm 110 is at its upper position (Figure 15) roller 168 is within the inner cam track 169 of cam structure 165, and semaphore 111 is in the horizontal position as shown in Figs. 12 and 15. Cam track 169 is semicircular, and as the arm 110 swings downwardly no change in the position of the semaphore takes place. However, towards the end of such downward movement roller 168 lifts a pivoted cam track section 170 and passes beyond it. Section 170 is spring-biased by means of a lever 171 fixed to the outer end of its pivot shaft, as shown in Figs. 15 and 16. The biasing spring 172 is of the compression type carried by a rod 173 which is pivoted at one end to lever 171 and at the opposite end to the cam structure 165.

Because of this construction, as soon as roller 168 passes beyond pivoted track section 170, the track section springs back to the position shown in Fig. 15. Consequently, on the upward movement of arm 110 roller 168 rides up the outer surface of the inclined track section 170, thus causing rack 152 to move upwardly, and, through pinion 164, swing the semaphore 111 downwardly to vertical position substantially in line with the arm 110.

When arm 110 reaches the end of its upward stroke, where it is shown in Fig. 15, roller 168 passes downwardly through an aperture 175 in the outer cam track 174. This downward movement of rack bar 152 is caused by the spring 166 at the bottom (Figure 12). However, in order to insure the upward swing of the semaphore 111 the force of spring 166 is not wholly relied upon, and cam 167, previously mentioned as on the lower surface of finger 107, engages the upper end 176 of rack bar 152 and forces it downwardly. The outward movement of fingers 107 takes place simultaneously with the return of arms 110 to their upper position.

Station B—the flap folding mechanism

It was mentioned previously that at the completion of the opening and squaring-out operation at station A the right upper corner 112 of the case is advanced against the circular stop plate 113 (Fig. 1) and held there by holders 14. At station B, at which point the case is completely squared-out in rectangular position, the case rests on its side on rails 46 and 47 and with the opposite side of the case at the top pressed against the pressure strips 115. With the case thus resting on its side the bottom flaps are on the front of the machine, that is, near the side in Figs. 5 and 6, and the top flaps are on the rear side.

All of these flaps, when the case arrives at station B extend straight out in the planes of the four sides of the case. Their score or hinge lines are stiff, and the object at station B is to "break" certain of the flaps, that is, bent them along their score lines, but not to fold them to closed position, which would require that the case remain in stationary position for a larger period of time, and thus interfere with the timing program of the apparatus.

In other words, at station B the flaps, for example, on the near side of the case and which eventually form the case bottom, have their hinge lines broken and are folded only partially toward closed position. Their complete closing occurs at station C. Thus the outer horizontal flap 103a which is at the upper side of the case is first

lifted slightly in order to allow the inner flaps, that is, the two vertical flaps 104 and 104a to be bent inwardly (Figures 7a and 10).

The mechanism for accomplishing this is shown in Figs. 1, 5, 6, 7, 7a, 7b and 24. The devices for folding the inner or vertical flaps 104 and 104a comprise two L-shaped flap tucking arms 177 (Figure 6) which are arranged symmetrically to each other and which have upstanding flap contacting fingers 178 fixed to their outer ends. Tucking arms 177 are fixed to a pair of short vertical shafts 179 (Figure 5) which are mounted for rocking movement in bearings 180 provided at the upper end of brackets 41. The flap tuckers 177 are adjustable on shafts 179 to accommodate cases of different size.

The lower ends of these shafts 179 have bevel pinions 181 (Figure 24) fixed to them which are rotated by bevel gears 182 fixed to a short lengthwise shaft 183, that is journaled in brackets 41. This is a rock shaft which is actuated by an arm 184 fixed on its left end and carrying a roller 185 operating within the cam track of a cam 186 on shaft 20 (Figures 5 and 7). From the shape of this cam track it will be understood that flap tucker arms 177 are periodically swung from their outer or dotted positions in Fig. 6 to their inner or full line positions. Hence, they swing the flaps 104 and 104a inwardly only from about 30 to 45° from their original straight out positions.

Before such flap movement can take place however, the horizontal outer flap 103a must be raised slightly, as previously mentioned. To first lift this flap and later fold it downwardly to partially closed position, the mechanism shown particularly in Figs. 6, 7, 7a and 7b is provided. A sprocket 187 fixed on cam shaft 20 drives an endless chain 188 which, passing an idler sprocket 189, is trained around a sprocket 190 (Figure 1) which is of the same diameter as sprocket 187 and which is fixed at the right-hand end of a short horizontal shaft 191 (Figure 6).

This shaft 191 is supported at its right end in a bearing in housing member 193 which is mounted at the upper end of a post 194 (Fig. 7) that projects upwardly from bracket 42. Shaft 191 carries at its left end the disk 113 which forms the stop for limiting the advance of the case when moved to position B. Parallel with shaft 191 is a second and somewhat longer shaft 192 (Figures 5 and 6). This shaft also has a bearing at its right end in housing 193. The two shafts are interconnected by a pair of similar intermeshing gears 195 so that the two shafts rotate at the same speed in opposite directions.

At its left end the outer shaft 192 carries a flap lifting finger 196 (Figure 7a). This finger rotates in a clockwise direction and lifts the horizontal flap 103a to the position shown in Fig. 7a, and the timing of this finger with the operation of the L-shaped flap tucking arms 177 causes the two vertical flaps 104 and 104a to begin to move inwardly while the outer flap 103a is lifted.

The inner shaft 191 has a short arm 197 (Figures 6 and 7) clamped to it at the right of disk 113. A horizontal rod 198 is secured to and projects toward the left from this arm. In order to aid in supporting rod 198 it rests in a shallow notch formed in the edge of disk 113 (Figure 7). Two arcuate members 199 (Figs. 1 and 7) are secured in fixed position and in parallel relationship to each other at spaced points on rod 198. The outer curved surfaces of these arcuate members are disposed at an increasing radial distance from the shaft 191. They engage the outer surface of the horizontal flap 103a, after it has been released from the finger 196 and swing it downwardly. After release it springs back approximately to the position shown in Fig. 7b.

Also while the case is at station B, the leading inner top vertical flap 104t on the far side of the machine is folded about its hinge line forwardly and then held in this position so that when the case is advanced to the packing station C this flap will clear the funnel of the packing mechanism 3. The mechanism which operates upon this flap is shown in Figs. 1, 5, 6 and 7. This mechanism comprises

a flap folding finger 200 which projects downwardly from the end of a horizontal arm 201.

This arm 201 is fixed to the lower end of a vertical supporting rod 202 which, in turn, is suspended in fixed position at the outer end of a two-armed webbed member 203. Member 203 is pivoted on a vertical post 204 which is mounted on and projects upwardly from the machine superstructure (Figures 1 and 5). The arrangement is such that although the webbed member 203 is pivoted at about the lateral centre of the machine, the flap folding finger 200 is disposed at the rear of the machine and swings in an arc about the pivot 204.

The actuation of the flap folding finger 200 is caused by a swinging movement imparted to webbed member 203 by means of a small constantly rotating crank 205, which is operatively connected to a short actuating arm on member 203 by means of a connecting rod 206. Crank 205 is fixed to the upper end of a vertical shaft 207 (Figure 7). This shaft is rotated by bevel gearing 208 which connects the lower end of shaft 207 with the horizontal shaft 89.

When the mechanism just described moves the flap folding finger 200 to the dotted position shown in Fig. 20 (sheet 13), the leading vertical flap 104t has been swung outwardly about its hinge through an angle more than 90°. At this instant the reciprocating carriage 51 is at the extreme forward or left-hand end of its stroke. Carriage 51 supports at its rear or right-hand end a pivoted flap holding finger or "sword" 209 (Figure 22). Finger 209 is pivoted at 210 and spring-biased to its upper or flap engaging position, as shown in Fig. 22 by means of a coil spring 211 (Figure 21). The finger is held in this position by means of a stop pin 212 which projects from the inner side of the vertical plate which is the principal member of carriage 51.

As shown in Figs. 20 and 22, the upper end of finger 209 lies outside of the folded flap 104t and projects above the lower edge of this flap. Holding finger 209 has been moved to this position by the motion of carriage 51 just after the flap folding finger 200 has folded the flap into the position shown in Fig. 20. The flap folding finger 200 now recedes towards the full line position shown in Fig. 6, and as the flap folding operations at station B have been completed, carriage 51 commences a forward stroke toward the right.

The case pusher 56 on the carriage, having slid beneath the bottom case and having risen at the left side of the case, pushes the case from station B to packing station C. During this forward movement the flap holding finger 209 retains the leading top flap 104t in the back-folded position of Fig. 20, so that this flap clears the funnel of the case packing mechanism 3. When the case reaches station C, a second pair of case holders 213 (Figure 19) spring upwardly and hold the case in this position.

Also at this same time a tail portion 214, which is provided on flap holding finger 209, engages a cam member 215 mounted in fixed position on the inner side of frame plate 26 and causes the finger 209 to be retracted, or lowered to the position shown in Figs. 19 and 21, thereby releasing the flap 104t and allowing it to spring towards the side of the funnel. Finger 209 is thus free of the flap and ready to move to the left with the next movement carriage 51.

During the movement of the case from station B to station C, the outer bottom flap 103, the horizontal flap at the lower side of the case, engages a stationary curved folding bar 216 (Figure 5) and is swung thereby from the position shown in Fig. 7a to about the position shown in Fig. 27. This bar is supported by suitable brackets on the frame of the machine.

Also the opposite or upper horizontal flap 103a is guided during the case movement to packing station C by means of stationary bars 217, 218 (Figure 5) which are mounted on the machine frame, the flap being trans-

ferred from one bar to the other as the case approaches station C. The left end of bar 217 is provided with a downward extension 219 and the feeding arrangement of the case by the carriage 51 is such that the case begins to advance while flap 103a is still engaged by the two arcuate flap folding members 199 (Figures 7a and 7b). In this way the lower edge of the flap is moved behind, that is, on the far side of the vertical extension 219.

Station C—the packing mechanism

With the case fully advanced to packing station C and held there by the holders 213, it is in alignment with the funnel 220 of the packing mechanism 3. A case is shown in phantom view in this position in Fig. 27, and also in Figs. 5 and 6. As shown in Fig. 27 the forward or top edge of the case is spaced slightly from the forward edge of funnel 220 and the leading inner top flap 104t is still held in its bent back position by the holding finger or sword 209. As soon as the carriage 51 commences its backward stroke, this finger will release the flap and it will spring towards the funnel side, as previously mentioned.

In Fig. 27 the case is ready to be pushed onto the funnel by the pusher plate 221. This is an elongated plate supported on two parallel rods 222 (Figure 6) which are hinged to two pairs of parallelogram links 223. The lower ends of these links are supported on two parallel shafts 224 which are mounted between brackets 43 and 44. The outer parallelogram links are keyed or pinned to the outer shaft 224 and the plunger plate 221 is actuated by rocking this shaft. For this purpose an arm 225 is clamped to the outer shaft 224 (Figure 5) and carries at its lower end a roller 226 engaging the edge of a cam 227 which is fixed to cam shaft 20. The roller is maintained in contact with the cam by means of a compression spring 228 (Figure 27) which is operatively connected to a short arm 229, also clamped to shaft 224.

As shown in Fig. 27 the plunger 221 is at the end of its outward stroke, and cam 227 is about to cause the plunger to advance to the dotted position and push the empty case onto funnel 220. During such movement the bottom of the case slides crosswise on the supporting rails 46 and 47. The plunger is within the outer flaps 103 and 103a and presses against the two inner flaps 104 and 104a (Figure 10).

The packing mechanism 3 (Figures 1, 6, 6a, 23 and 27) is of the kind disclosed in Patent No. 2,127,924, granted August 23, 1938, to W. D. Kimball, Cornelius I. Braren and George P. Schaefer, except that it is arranged to pack four rows of six cans each instead of four rows of three cans each.

The cans are delivered in a single line by means of an inclined chute 230 (Figures 6a and 23—sheet 9) into the mouth of a dividing apparatus 231 which distributes the cans equally onto four runways 232 superposed one above the other, and by means of which they are conveyed to four superposed shelves 233 (Figures 6a and 27). The cans roll on their sides along the chute through the dividing apparatus and along the runways and shelves 233. After a tier composed of six cans on each of the four shelves 233, is formed, these twenty-four cans are pushed endwise by pushers 234 off the shelves 233 and into the funnel 220 (Figure 6a), through which the cans are pushed by the pushers until they are received within the case.

The can packing mechanism is driven by an independent source of power (not shown) which is connected to rotate the main shaft 235 (Figure 6a) continuously. This shaft, through a one-revolution clutch, indicated diagrammatically by numeral 236, drives an operating cam 237 which causes the pushers 234 to operate in such manner that a complete charge of twenty-four cans is placed in the case each time the one-revolution clutch is tripped. This clutch is tripped by the

energization of a solenoid 238 to be referred to again. It will be understood that each of the pushers 234 pushes a row of six cans into the case, and the pushers are actuated by cam 237 through the upper and lower bent arms 239 and links 240 (Figures 6 and 6a). Arms 239 are pivoted to the packing mechanism frame at 241.

The packing mechanism frame is supported on pedestals, one of which is shown at 242 in Fig. 1, the other pedestal being to the right of the apparatus and not shown. These pedestals are connected together by longitudinal tie members 243. The packing mechanism frame also includes upper longitudinal bars 244 and these are connected with the frame of the case opening and positioning mechanism 2 by means of one or more cross-tie bars 245 (Figures 5 and 19).

As a charge of cans has been pushed into the case at station C, as above described, the stroke of the pushers 234 may be long enough to push the case off of funnel 220 and return it to its former centered position on the supporting rails 46 and 47. However, in order to insure that the case is released from the funnel and centered on the rails, a case release or push-off device 246 is provided (Figure 25).

Such device 246 is in the form of a rigid pocket member to receive the lower horizontal top flap when the case is pushed onto the funnel. Push-off 246 is secured at the top of a lever 247 which is pivoted at 248 to a bracket mounted on the outer surface of stationary frame plate 26. The lower end of lever 247 is connected by means of a rod 249 with the lower end of a second lever 250 having a roller 251 which operates on the face of a cam 252 on shaft 20. A coil spring 253 arranged on rod 249 maintains the roller in engagement with the cam.

It will be understood from the shape of cam 252 that the push-off 246 is momentarily forced to the right in Fig. 25 and engages the inner edge of the case flap 103t, which is the one along the lower side of the case on the funnel, and through this flap moves the filled case as above described.

Control mechanism

It will be understood that the operation of the packing mechanism 3 is coordinated with that of the case opener and positioner mechanisms 1 and 2. This is accomplished electrically and will be understood by referring to Fig. 23 (sheet 8). The motor 14 which drives the case opening and positioning mechanisms, is fed from a three-phase supply 254 and is controlled by means of a solenoid-operated main switch 255 arranged to open all three of the supply leads. The one-revolution clutch 236 which controls the packing mechanism 3 is actuated by a solenoid 238, as previously described.

The energization of the operating coil of this solenoid 238 is controlled by a cam-operated switch 256 which is operated by a cam 257 on cam shaft 20 (Figures 1 and 5), this switch serving to time the operation of the packing mechanism with respect to the operation of the case opener and positioner mechanisms. Thus, the circuit for energizing the coil of solenoid 238 may be traced from one side of the supply 254 through a conductor 258 to the contacts of switch 256, thence through a wire 259 to the contacts of a case detector switch 260, which are closed only if a case has been properly positioned on the funnel 220 (see Figures 7 and 19).

This circuit continues through a wire 261 to the solenoid coil 238 and thence through a lead 262 back to the conductor of the supply 254. Thus, assuming that the main switch 255 has been closed, thus starting the main motor 14, and also assuming that there is a continuous supply of cans to the can packing mechanism, the solenoid 238 will be energized momentarily at each revolution of the main cam shaft 20, thereby causing a charge of cans to be inserted in the case at the packing station C at the proper time with respect to the operation of the remainder of the apparatus.

For the purpose of closing the main switch 255, a circuit may be traced from the center conductor of the supply 254 through a lead 263 to the normally closed contacts of a manual stopping switch 264, whose contacts are maintained closed by means of a compression spring in a conventional manner. The circuit then continues through the operating coil 265 of main switch 255 to conductors 266 and 267 to the contacts of a manual starting switch 268. These contacts are normally held in open position by a compression spring in a conventional manner. From the contacts of this switch the circuit continues through a wire 269 to a conductor 270 which is connected with one of the outside leads of supply 254.

By pushing the button of the starting switch at 268 a circuit will be closed through coil 265 and this will cause the closing of the contacts of main switch 255. This switch includes a set of holding contacts 271 which are closed when the power contacts of the switch are closed. The closing of contacts 271 completes a holding circuit from conductor 266 through wire 272, the contacts 271 and wire 273, thence through the contacts 274 of a can-operated switch and thence through a wire 275 back to one of the outside conductors of supply 254. Hence, the momentary closing of the starting switch 268 will cause main switch 255 to be closed, and the holding circuit, just described, will maintain it closed until such time as the stopping switch 264 is operated.

The case opening and positioning mechanism of the present invention operates at a higher rate of speed than the can labeling machine which supplies cans through the chute 230 to the dividing apparatus 231 and thence along the runways 232 to the shelves 233 of the packing mechanism. Accordingly, it is desirable to interrupt the operation of the case opener and positioner during the periods of inadequate flow of cans from the labeler. This may be accomplished, if desired, in the manner set forth and claimed in Patent No. 2,289,820, granted July 14, 1942, to Edgar Ardell and owned by the same assignee as the present application.

Two switches, the low can-supply stopping switch 274, previously referred to, and a high can-supply starting switch 276 each actuated by its own pivoted and counterbalanced runway section disposed in one of the runways 232, is provided. The low switch contacts 274 in the holding circuit maintain operating coil 265 of the main switch energized. The high switch 276 is connected in parallel with the contacts of manual starting switch 268 by means of wires 277 and 278.

Accordingly, assuming that the machine has been started, as described above, the cans in the runways 232 will be gradually depleted from the position shown in Fig. 23 until the supply of cans is below, or to the left of, the runway section which operates low switch contacts 274. With the weight of the cans removed from this pivoted section, the contacts 274 will be opened, thus breaking the circuit of coil 265, opening main switch 255 and stopping motor 14. The case opener and positioner mechanism will remain shut down until the supply of cans on the four runways 232 has built up sufficiently to cause the closing of high switch 276. This re-starts the motor 14 in the same manner as described above when the manual starting switch 268 was closed.

Station D—the case drop-off mechanism

As soon as the filled case has been pushed off the funnel of the packing mechanism at station C, carriage 51 through its right-hand case pusher 57 (Fig. 19) advances the case from station C to the drop-off station D (Figure 5). During this movement the top leading inner flap 104 is folded to closed position by engagement with the left edge of load-retaining plate 279 which forms part of the drop-off mechanism.

The drop-off mechanism (Figs. 1 and 28-31) receives the case while in vertical position, that is, resting on its side as shown in Fig. 28 and turns the case through an

angle of 90° and deposits it in upright position, as shown in Fig. 29 on the conveyor 7 (Figure 6). The drop-off arm which is indicated generally by numeral 280 is keyed to the lower of two parallel rock shafts 281 and 282. These shafts are journaled in suitable brackets mounted on the front face of frame plate member 27 (Figure 5).

The drop-off arm 280 is a composite structure comprising a crooked section 283 which is keyed to shaft 281 and which terminates in a head having a circular bore to receive the shank 284 of a case-supporting member 285 (Figure 29). This permits the shank 284 to be adjusted in the head of arm 283 both for different size cases and also to correctly position the case-supporting member 285 with respect to the case-supporting rails 46 and 47 when the drop-off arm is in the receiving position as shown in Fig. 28. For the same reasons case-supporting member 285 is adjustable (by means not shown) laterally with respect to its shank member 284.

Just before the drop-off arm 280 reaches vertical position (Figure 28) the case is advanced by carriage 51 along rails 46 and 47 into position between the drop-off arm and charge-retaining plate 279. As the drop-off arm reaches the vertical position the case is forced between a plate-like spring member 286 on the upper side of the case and a supporting member 287 on its lower side. Both of these members are flared outwardly at their ends to facilitate their movement onto the case.

Supporting member 287 is mounted upon the head of crooked section 283 of the drop-off arm by means of a pair of threaded rods 288 which are welded to member 287 (Figure 29) and which project through apertures in lugs which are formed on the opposite sides of the head of section 283. These threaded rods are secured in place each by a pair of nuts as indicated. In this way the position of member 287 may be adjusted with respect to the height of the spaced supporting rails 46 and 47.

The drop-off arm 280 is oscillated between the vertical position of Fig. 28 and the discharge position of Fig. 29 by rocking movement imparted to shaft 221 through the mechanism shown in detail in Fig. 26. This comprises a crank 289 fixed to the end of cam shaft 20 (Figure 5) and connected to an actuating arm 290 fixed to the left-end of upper shaft 282 by a connecting rod 291. The sector gear 292 on shaft 282 drives a pinion 293 on the lower shaft 281 on which the drop-off arm 280 is mounted. The length of the two crank arms 289 and 290 and the radii of the sector gear 292 and pinion 293 are so chosen that during each revolution of shaft 20 the drop-off arm 280 is rotated through an angle of somewhat more than 90°, as will be seen by comparing Figs. 28 and 29.

In the former figure the drop-off arm is at the top of its stroke and is exactly vertical. In Fig. 29 the drop-off arm is at the bottom of its stroke, as indicated by the full-line position of crank 289, and has been moved through an angle somewhat greater than 90°. The case has been deposited on the horizontal endless conveyor 7 and the drop-off arm has moved below this point sufficiently to substantially disengage the plate spring member 286 from the outer lower corner of the case so that the case can be moved forward by the conveyor.

The purpose of the charge-retaining plate 279 is to prevent the charge of cans or other articles from being dislodged from the case because of their inertia at the beginning of the drop-off movement and the quick action of the drop-off arm. The plate is sufficiently large to reach all of the articles of the charge, although it is somewhat smaller than the top of the case, and the plate is caused to move in engagement with the top of the case during the first part of the drop-off movement. The plate is then returned to its initial position during the remainder of the drop-off movement.

This load-retaining plate 279 is bolted at one end (Figure 30) to a supporting arm 294. The hub of this arm turns freely on shaft 281 after the arm 294 and plate 279 have followed the case downward to a predetermined

angle or position. They are returned to their initial vertical position by means of a swinging arm 295 which is fixed to the upper shaft 282, in a manner to be described presently. When arm 294 and plate 279 reach their initial vertical position, they are latched there until the drop-off arm 280 next swings back to its upright position to receive the next or succeeding case.

This latching mechanism will now be described and following that, the operation of the drop-off mechanism through a complete cycle will be given.

The latch mechanism is shown in detail in Fig. 31 and also in Figs. 28, 29 and 30. It comprises two inter-engaging latch members. One of these, 296, is fixed to and projects horizontally from arm 294 when this arm is vertical. The other latch member 297 is on the horizontal portion of an L-shaped lever 298 which is pivoted on a pin 299 that projects rearwardly, that is, to the right in Fig. 29 of the frame plate 26. The tension coil spring 300 (Figure 31) tends to maintain latch members 296 and 297 in engagement, this spring being attached at one end to frame plate 26, and at the opposite end to lever 298 above its pivot.

The latch is tripped by means of a finger 301, fixed to the end of lower rock shaft 281, which engages an elongated pin 302 that projects from a tail portion of lever 298 below pivot 299. Engagement of these parts and the tripping of the latch occurs at a instant the drop-off lever reaches the end of its upward stroke, that is at its vertical position (Figure 28). This releases the latch and allows the plate 279 to be moved against the top of the case by means of a heavy tension coil spring 303 which is attached at one end to a bracket mounted on the rear of the frame plate 26, and at its opposite end to an arm 304 which projects downwardly from the side of the hub of supporting arm 294.

The angular travel of the swinging arm 295 is considerably less than that of the drop-off arm 280, since its function is merely to return the charge-retaining plate 279 to its vertical position after it has followed the case on arm 280 downward, for example, to the angular position shown in dotted lines in Fig. 28. It is important to have plate 279 follow the loaded case during its initial movement so as to overcome the inertia of the charge and until gravity operates to hold the cans firmly against the bottom or left end wall of the case as viewed in Fig. 28. It will be understood that all of the top flaps of the case project upwardly except the leading top flap 104_t which was folded to closed position by the plate 279 as the case was advanced from station C onto the drop-off mechanism, as shown in Fig. 28. This flap springs up somewhat after the return of plate 279 (Figures 11b and 29).

The operation of the drop-off mechanism through a complete cycle will now be traced.

The angular movement of swinging arm 295 depends upon the ratio of the length of the crank 289 to that of the arm 290. As shown in Figs. 28 and 29 it is in the neighborhood of 60°. It will be understood that, due to the sector gear 292 and pinion 293, the swinging arm 295 and the drop-off arm 280 always move in opposite directions so that, starting with the drop-off arm in a vertical position (Figure 28), swinging arm 295 is at the lower end of its stroke. With the parts in this position the crank 289 is at its outer dead centre position, as shown by dotted lines in Fig. 29.

As the crank rotates, the drop-arm 280 commences to move downwardly toward the left in Fig. 28, and simultaneously the swinging arm 295 commences to move upwardly. When the drop-off arm reaches the dotted position a roller 305 which projects from the outer side of arm 295 engages the front surface of a pad 306 which projects from the inner surface of supporting arm 294 for the charge-retaining plate 279. Hence, during the continuing downward movement of the case and drop-off arm 280, the continuing upward movement of

swinging arm 295 moves the charge-retaining plate 279 back to its vertical position.

As it reaches such position the latches 296 and 297 engage one another and lock the supporting arm 294 and the charge-retaining plate in this position. At the same time that these parts reach the vertical position, the drop-off arm 280 reaches the lowermost part of its stroke (Figure 29) where the case is deposited on the conveyor belt 7 and released from the drop-off arm. Time is provided for the conveyor to remove the case during the dwell of the parts caused by the crank 289 now being at its inner dead centre position (full lines in Figure 29), and the time required before the drop-off arm, on its upward stroke, passes through the horizontal position.

At the same time the swinging arm 295 commences its downward movement from the full-line position of Fig. 29 towards the dotted line position of that figure and the full-line position of Fig. 28. The latch mechanism 296, 297 retains the retaining plate 279 and its supporting arm in the vertical position during such downward movement of the swinging arm 295. When the drop-off arm 280 again reaches the vertical position (Figure 28), the finger 301, which is fixed to the end of the drop-off arm shaft 281 contacts the elongated pin 302 thereby releasing the latching mechanism, and a succeeding drop-off operation commences.

The case blank or collapsed case magazine

This is indicated by reference numeral 1 and shown in Figs. 1, 2-4 and 32-36. As stated near the beginning of the description the collapsed cases are supported on their rounded edges on a horizontal bed 5. Preferably this bed is provided with wear strips 307 of nylon or other low friction material (Figure 35). Bed 5 is a rigid channel member supported at the right or forward end by a frame member which is mounted approximately centrally of the apparatus on the frame rods 9 (Figures 4 and 12). At the rear left end the bed 5 is secured to a bracket member 308 (Figures 2, 3 and 32) which is mounted in fixed position on a cross-rod 309.

This cross-rod is supported at its opposite ends in bracket members 310 which are adjustably supported on two spaced vertical pedestal rods 311 that project upwardly from the floor and constitute the rear frame member of the case magazine section 1. The upper tie rod 309 forms a brace between the upper ends of the vertical rods 311. The case blanks in the supply 4 are maintained in centered position on the bed 5 by means of two horizontal parallel guide plates 312 at the rear of the magazine, and shorter, somewhat similar guide plates 313 at the front.

Thus the front guide plates are supported only at their right-hand ends and are mounted on the upright frame members 120. The two rear guides 312 are supported only at their centers and are mounted on an upright stationary rod 314 which is supported at the bottom on a cross-member 315 that is carried upon two parallel, longitudinal rods 316 extending between the two pedestal rods 311 and the frame members at the right-end or front end of the magazine.

The two pairs of feed members 6, upper and lower, are substantially alike, and are supported, operated and manipulated by substantially similar mechanisms. Such mechanism is shown in detail in Figs. 32-36 for the lower pair of feed members 6. These lower and upper mechanisms are supported on two similar rigid hollow rods 317. The lower rod 317 is mounted at its left end in bracket member 308 and at its right end in a bracket 318 (Fig. 4) which is carried on the two left frame cross rods 9. The upper hollow rod 317 is supported at its left end in upper bracket 308 which is mounted upon the upper cross-bar 309. At its right end the upper rigid hollow rod 317 is supported in a bracket 319 (Figure 4) which, in turn, is secured to a cross-rod 320 (Figs. 4

and 12) extending between the two upright frame members 126.

Referring now to Figs. 32-36, the rigid hollow rod 317 has lower and upper parallel, approximately rectangular channels 321 cut therein which extend lengthwise for somewhat more than one-half the length of the rod. Mounted in fixed position in the lower channel 321 of each rod is a ratchet-holding rack 322. In the upper channel 321 there is a similar lengthwise movable feeding rack 323. This rack is moved and biased towards the left by means of a pivoted lever 324 (Figure 33). This lever rocks on a horizontal pin 325 fixed in bracket member 308. At its upper end it is forked to receive a horizontal pin 326, the outer end portions of which project on either side of rack 323. A compression coil spring 327 is arranged on the lower side of pivot 325 to urge the lower arm of lever 324 against an adjustable stop 328 and retract the movable rack 323.

The two lower feed members 6 are mounted upon a carriage 329 which slides on the lower rigid hollow rod 317 (Figures 32 and 35) and carries ratchets which engage the holding and feeding racks 322 and 323 in such a way that the longitudinal movement of the feeding rack causes carriage 329 and the feed members 6 to advance toward the right. Carriage 329 and its mechanism will be described presently.

The mechanism which imparts the reciprocating motion to the feed rack 323 will now be described.

The endless chain 330 which is driven from a sprocket on cross-cam shaft 17 (Figure 12) is trained around a sprocket on a short shaft 331 (Figures 2 and 32-34). This shaft is journaled in lower bracket member 310 and in the lower part of bracket member 308. On the front end of shaft 331 which is at about the lateral centre of bracket 308, there is a crank pin 332. The forked lower end of the lever 333 straddles this crank pin whereby the lever is caused to have a continuous rocking movement about its supporting pivot 334.

A driving dog 335 is pivoted at 336 to the upper end of this lever. This dog has at its right end a nose 337 which, under certain circumstances, engages a shoulder 338 on feed rack 323 and moves the rack to the right. Under other circumstances the nose 337 is held in elevated position so that the dog reciprocates without driving the rack.

The elevation of the dog 335 is controlled by means of a trigger lever 339 pivoted at 340 at its lower end to bracket 308. At its upper end lever 339 has a rounded, forward corner which is the controlling surface of the lever and which engages a pair of rollers 341 pivoted on the opposite sides of dog 335 on a transverse pin 342 which is fixed in an aperture in the dog and projects from both sides thereof (Figure 34). Urging the dog 335 downwardly with some considerable force are a pair of tension coil springs 343 which are attached at their upper ends to the pin 342, one on each side of the dog, and at their lower ends are fixed to bracket 308.

When the trigger lever 339 is moved slightly to the left, as shown in Fig. 33, its rounded corner is moved sufficiently to allow the rollers 341 to move down this rounded surface and allow the nose 337 of the dog 335 to be lowered sufficiently so that on the next reciprocation of lever 333 the nose of the dog will drop behind shoulder 338 and push the feed rack 323 forward to the right. This causes the feed members 6 to be advanced as will be explained presently.

The length of the advance depends upon the setting of the adjustable stop 328 for the biasing lever 324. It may be a distance equal only to one tooth of rack 323, or it may be as much as two of these teeth.

When the trigger lever 339 is rocked to the right, as shown in Fig. 33a, it causes the roller 341 of dog 335 to ride up on the curved corner of the lever and raise nose 337 so that on the next rocking movement of lever 333, the dog will descend on the flat surface 344 to the

right of shoulder 338 so that no feeding movement of the rack 323 will occur. Whether or not the trigger lever 339 is held in the non-feeding position of Fig. 33a, or shifted to the feeding position of Fig. 33, depends upon the position of a lower feeler member 345, shown in Fig. 4.

This member 345 is pivoted at 346 in a vertical slot in the right end of lower rigid hollow rod 317. It has an upwardly extending feeler finger 347 which is engaged by the foremost collapsed case or blank 99. An upper feeler member 345, which is similar to the lower except that its finger 347 projects downwardly, is mounted at the right end of the upper rigid rod 317. These feeler members each have a slot-type cam 348 which engages a horizontal pin 349 that is held in the slotted end of a fitting which is mounted on the right end of a control rod 350, one of which is slideable in the hollow centre of each of the lower and upper rigid rods 317.

Referring again to Fig. 33 the left end of the lower control rod 350 is shown as being connected to the trigger lever 339. For this connection a lateral aperture is made in the trigger lever and a pair of vertical slots are formed in the portions of the lever on the opposite sides of this aperture. Close to the end of rod 350 there is a transverse pin 351 (Fig. 33a) which projects from the opposite sides of the rod and engages the two vertical slots to rock lever 339 about its pivot 340 and shift the upper end of the lever to raise or lower the driving dog 335.

The upper control rod 350 is similarly connected to the trigger lever 339 for the upper feed mechanism, as will be referred to below.

It will be understood that when the foremost collapsed case 99 has been removed from the right end of the horizontal stack or supply 4 (Figure 4), the feeler fingers 347, both upper and lower, will be swung outwardly by the case. This causes them to rotate on their pivot bringing the outer and steeper portions of their slotted cams 348 into engagement with the pins 349. As soon as the foremost case is pulled from the end of the supply 4, the feeler fingers 347 are rotated backward into contact with the next case blank of the stack.

This rotation comes about through the tension of the two coil springs 343, shown in Fig. 34, which cause the rollers 341 to press against the rounded corner of trigger lever 339 and thus urge this lever backward or towards the left. This shifts rod 350 which, acting through pins 349 and the slotted cam 348, tends to rotate its feeler member 345 in the direction to cause its feeler finger 347 to return against the next case blank.

Should the next case blank be sufficiently far to the right, the left-hand movement of rod 350 and trigger lever 339 will be arrested while the nose 337 of the driving dog 335 is raised sufficiently to prevent it from engaging shoulder 338 on the next reciprocating movement of the dog and thus prevent a feeding movement from being imparted to the feed rack 321 and through this to carriage 329 and feed members 6. However, when one or more additional case blanks have been removed from supply 4, the motion of rod 350 to the left will be sufficient to allow the dog to drop enough to engage the shoulder 338 and cause a feeding movement of the supply 4 to take place.

The mechanism shown in Figs. 32-34 is duplicated at the top of the magazine section 1 except for the changes necessitated by the operation of the upper feed members 6 in contact with the upper left-hand corner of the horizontal stack or supply 4, instead of against the lower left-hand corner of the stack. Such changes will be referred to presently in connection with a detailed description of carriage 329.

The upper crank shaft 331 and crank 332 are rotated continuously by means of endless chain 352 which is driven from the lower crank shaft 331 (Figure 2). The upper control rod 350 (Figure 4) is connected at its

front end with the upper pivoted feeler member 345, as previously described. At its left end the upper rod 350 is connected to the upper trigger member 339 (not shown), but it will be understood that the construction is precisely the same as shown in Fig. 33. It will be understood that the upper trigger lever 339 is controlled by upper feeler member 345 independently of the control of the lower trigger member 339 by the lower feeler member 345.

However, the two upper and lower driving dogs 335, whose operation is controlled by their respective trigger members, are interconnected by means of a vertical rod 353 which is made in two sections connected together by a turnbuckle 354 for adjustment purposes. The lower end of rod 353 is pivoted to the front end of pin 342, as shown in Fig. 34. The upper end of the rod is similarly pivoted to the corresponding pin 342 on the upper dog member 335.

By the interconnection of the two dog members 335, if either the lower or the upper pivoted feeler member 345 calls for a feeding movement, equal movement is caused to be imparted to both the lower and upper pairs of feed members 6. This keeps the two pairs of feed members always in step with one another regardless of whether the position of the bottom or the top of the forward or right end of the stack 4 causes its feeler member 345 to call for forward feeding of the stack.

Referring now more particularly to Figs. 35 and 36, the construction of lower carriage 329 will now be described. This is a sleeve-like casting arranged to slide freely on the lower rigid rod 317. On its lower side it has two parallel spaced vertical projections 355. At their lower ends these projections carry two rollers 356 which engage the opposite faces of a stationary rail 357 that extends lengthwise of magazine section 1 (Figures 2 and 3). Thus the carriage is maintained in upright position as it is moved forward or backward along its circular supporting bar 317.

The two feed members 6 are approximately L-shaped castings (Figure 3) with their horizontal arms pivoted at 358 to two lateral extensions 359 formed on each side of carriage 329. They can be swung from an upper position (Figure 32) to a lower position (Figure 36) for a purpose and by mechanism to be presently described.

In order to cause the carriage 329 to be fed forward when a feeding movement of rack 323 takes place, a feed ratchet 360 is pivoted at 361 in a central recess on the upper side of carriage 329, the left end of which is biased into engagement with the teeth of feed rack 323. Such biasing action is produced by means of a compression coil spring 362 which is arranged beneath the tail portion of the ratchet, as shown in Fig. 36. Carriage 329 is held in its advanced position, during the retractive movement of feed rack 323, by means of a holding ratchet 363 pivoted at 364 midway between the two parallel projections 355. This ratchet is biased into engagement with the teeth of the stationary lower rack 323 by means of a compression spring 365.

Referring to Fig. 32 it will be understood that when a feeding motion to the right of rack 323 occurs, this motion will be transferred through the ratchet 360 to carriage 329 and the teeth of the holding ratchet 363 slide over one or more of the teeth of the stationary rack 322. Then on the retractive movement of rack 323 to the left, one or more of its teeth pass beneath the ratchet 360.

When the stack or supply 4, as shown in Fig. 1, has been depleted by the removal through the opening and squaring-out of successive case blanks from the right end of the stack by the operation of the machine, the stack is replenished by adding a new group of collapsed blanks in edgewise position at the left of the depleted stack. It is now necessary to move the upper and lower carriages 329 from engagement with the rear end of the depleted stack to the rear end of the added group. To do this the two lower feed members 6 are swung downward to

the dotted position shown in Fig. 36 where they will clear the bottoms of the new case blanks; also the two upper feed members 6 are swung upwardly so as to clear the tops of the case blanks; also the two ratchets 360 and 363 are swung out of engagement with their respective racks.

Referring again to Figs. 35 and 36, the desired retracting movement of the feed members 6 and the two ratchets is accomplished by turning the hand wheels 366 on the upper and lower carriage 329. They are keyed to a shaft 367 which is mounted for rocking movement in bearings near the lower ends of the two projections 355. Also keyed to shaft 367 are two crank arms 368 which are connected by links 369 to the forward ends of the respective L-shaped feed members 6.

When, for example, the lower hand wheel 366 is turned to the right the position of the parts shown in Fig. 32, is such that a taggle linkage is formed, a stop (not shown) being provided which prevents further rotation of the shaft 367 towards the right. When it is desired to lower the feed members 6, the hand wheel 366 is rotated toward the left, as shown by the arrow, and this results in the downward swinging of the two feed members 6 as shown in Fig. 36. During this movement a pair of projections 370, one on each of the feed members 6 (Figure 32) engage collars 371 mounted near the opposite ends of a rod 372 which is fixed at its centre to the holding ratchet 363.

Rod 372 passes through arcuate openings 374 in downward projections 355 (Figure 32). The motion imparted to ratchet 363 releases it from the lower rack 322 (Fig. 36). Simultaneously, the upper or feed ratchet 360 is raised out of engagement with feed rack 223 by means of a pair of links 375 which are pivoted at their lower ends to a rod 376 supported at its centre by the tail portion of holding ratchet 363. At their upper ends these links 375 are connected to the tail portion of the feed ratchet 360. A slotted connection 377 is used at this point (Figure 32) in order to avoid interference with the normal operation of ratchet 360.

The construction of the upper carriage 329 is the same as that just described in connection with Figs. 32, 35 and 36, except that the two parallel projections 355 project upwardly from the body of the carriage, and the vertical portions of the feed members 6 project downwardly. In other words, the two carriages are alike except that the upper one is inverted with respect to the lower. The guiding rollers 356 are thus above the carriage instead of being below it, and the same is true of the upper guiding rail 357.

By means of the carriage mechanism just described, a replenishing group of case blanks can be very quickly added to the left end of the supply 4, and the feed member 6 quickly brought again into feeding operation with respect to the left end of the replenished stack.

The invention has been illustrated and described in connection with one embodiment thereof and it will be understood that changes may be made in the construction and arrangement of the apparatus, and that the scope of the invention is set forth in the appended claims.

We claim:

1. The method of opening and squaring-out collapsed shipping case blanks which comprises supporting a stack of such banks on its side with the individual blanks standing edgewise and with their flaps extending horizontally, bending outwardly to an acute angle one pair of the two outside pairs of flaps of the foremost blank at one end of said stack while engaging the other pair of said flaps to hold the blank against the stack, engaging the two flaps which are disposed inwardly of the two bent-out flaps and holding them during the squaring-out movement, releasing said other pair of flaps, pressing on the body portion of said blank outwardly and with a swinging action to square-out the blank, and thereafter pulling the squared-out blank from the stack.

2. The method of opening and squaring-out collapsed shipping case blanks which comprises supporting a stack

of such blanks on its side with the individual blanks standing edgewise and with their flaps extending horizontally, bending outwardly to an acute angle the opposite lower flaps on the outside of the foremost blank at one end of said stack while engaging the upper flaps of said blank to hold the blank against the stack, engaging the two lower flaps of the inner half of the blank and holding them during the squaring-out movement, releasing said upper flaps, inserting a pair of fingers from the opposite sides of the blank behind each of said bent-out flaps and behind the adjacent body portion of said blank, moving said fingers outwardly and downwardly to square-out the blank, and thereafter pulling the squared-out blank from the stack.

3. In a machine of the class described, a magazine containing collapsed shipping case blanks supported in edgewise position in a compact group, each of said blanks having two pairs of flaps on each face, mechanism for squaring out the foremost case blank at one end of said group comprising movable flap retaining devices, vacuum means for turning outwardly on its hinge at least one of said flaps on the outer face of the blank, means operable while said flap is held in said position for actuating one of said retaining devices into engagement with the adjacent flap on the inner half of said blank to hold it against said compact group, at least one pivotally mounted case opening member, mechanically operated mechanism for causing said member to enter behind said outwardly turned flap and engage the case body to swing the case blank partially open while said adjacent flap is held in said position, means for actuating said retaining devices to cause them to release the case, and means for advancing the partially opened blank away from said group.

4. A machine as set forth in claim 3 wherein the vacuum means comprise at least one vacuum arm pivoted at one side of the group of case blanks approximately in the plane of the foremost blank, means for swinging said arm into engagement with one of the flaps on the outer face of the blank, means for turning said arm in a general axial direction while in engagement with said flap to turn the flap outward, and means for swinging said arm in the opposite direction so as to clear the path of movement of a portion of the case blank as it is swung partially open.

5. In a machine of the class described, a magazine containing collapsed shipping case blanks supported in edgewise position in a compact group with their flaps extending horizontally, mechanism for squaring-out the foremost case blank at one end of said group comprising vacuum means for swinging outwardly about their hinges the flaps of one of the outer walls thereof, a device for maintaining the adjacent inner wall of the blank in contact with the next succeeding blank of said group, a pair of case opening members, mechanically operated mechanism for causing said members to enter behind said outwardly swung flaps and engage the case body and swing the case blank at least partially open while said adjacent wall is held in said position, means for causing said device to release the blank, and means for advancing the partially opened blank away from said group.

6. In a machine of the class described, a magazine containing a compact group of collapsed shipping case blanks supported in edgewise position, a case opening station including mechanism for opening the foremost case blank of said group to polygonal form with its flaps projecting in line with its walls, a flap-folding station having mechanism for folding the flaps at one end of the case blank in a predetermined manner, a packing station including mechanism for inserting a charge into the opposite end of the case, a case righting station including mechanism for turning the filled case from horizontal to upright position and depositing it upon a support, said stations being disposed side-by-side, a reciprocating conveyor including a reciprocating carriage and an elongated support on which the cases slide, said support extending from said opening

station to said righting station, said reciprocating carriage having means for receiving the opened case from said opening mechanism and for advancing it to the flap-folding station and having means for simultaneously advancing 5 previously opened cases from each of said remaining stations to the next station, and means for operating said righting mechanism in timed relation to said conveyor.

7. A machine as set forth in claim 6 wherein the mechanism at the packing station includes a funnel through 10 which the charge of articles is moved into the case at said station, and wherein the mechanism at the flap-folding station comprises a flap-folding member arranged to engage the forward inner top flap of the case at said station, and means for actuating said flap-folding member to 15 cause it to bend said flap forwardly, and a flap-retaining member pivoted on the reciprocating carriage, said carriage being arranged to move said retaining finger into engagement with said forwardly folded flap while it is held in such position by said folding member, said flap-retaining member serving to hold said flap in its forwardly bent position while the carriage advances said case opposite the funnel at the packing station.

8. A machine as set forth in claim 7 wherein means 20 is provided at the packing station to withdraw the flap-retaining finger from engagement with the forwardly bent flap, so as to permit said case to be telescoped onto the funnel of the packing mechanism.

9. In a machine of the class described, a magazine 25 containing a compact horizontal stack of collapsed shipping case blanks supported in edgewise position with their flaps extending horizontally, a case opening station including mechanism for opening the foremost case blank of said stack to polygonal form with the blank resting on one side of its body section with its flaps projecting in line with its walls, a flap-folding station having mechanism for folding the flaps at one end of the case blank in a predetermined manner, a packing station including mechanism for inserting a charge into the opposite end of the case, a case righting station including mechanism 30 for turning the filled case from horizontal to upright position and depositing it upon a support, a reciprocating conveyor including a reciprocating carriage and an elongated support on which the cases slide resting on their sides, said support extending from said opening station 35 to said righting station, said reciprocating carriage having means for pulling the opened case blank from the end of said stack and having means for simultaneously advancing previously opened cases from each of said remaining stations to the next station, and means for operating said righting mechanism in timed relation to said conveyor.

10. A machine as set forth in claim 9 wherein the mechanism at the flap-folding station comprises a pair of flap tuckers and means for actuating said tuckers to fold the two inner bottom flaps inwardly, and mechanism 40 operating to lift slightly the outer bottom flap at the top side of the case prior to the actuation of said flap tuckers so as to insure that said outer flap clears the path of the top edges of the two inner flaps.

11. A machine as set forth in claim 10 wherein mechanism 45 is provided at the flap-folding station for swinging downwardly the previously lifted outer flap.

12. A machine as set forth in claim 9 wherein the packing mechanism includes a funnel through which the charge is inserted in the case, and the mechanism at the packing station comprises a pusher arranged to operate on the bottom of the case and mechanism for operating said pusher to move the mouth of the case onto the funnel of the packing mechanism.

13. A machine as set forth in claim 9 wherein the packing mechanism includes a funnel through which the charge is inserted in the case, the mechanism at the packing station includes a case push-off device arranged to engage the outer top flap located at the lower side of the case, and mechanism for actuating said push-off device to cause it 50

to engage the horizontal edge of said flap and push the filled case from the funnel.

14. A machine as set forth in claim 9 wherein the mechanism at the case righting station comprises a case drop-off arm for receiving the case resting on its side, mechanism for actuating said arm through a righting movement to turn the case from horizontal to upright position and deposit it on a support, a load-retaining member for engaging the top of the case to prevent the contents from being displaced during said righting movement, a pivoted arm for supporting said retaining member, and means for actuating said arm to cause said member to follow said case during approximately one-half of said righting movement and then returning said retaining member to its initial position during the remainder of said movement.

15. In a machine of the class described including a case-packing station and case-righting station, mechanism at said packing station for inserting a charge of articles into a case supported on its side at said packing station, means for advancing successive cases from said packing station to said righting station, and mechanism at said righting station for turning the filled case from horizontal to upright position and depositing it upon a support, said mechanism comprising a case drop-off arm for receiving the case resting on its side, mechanism for actuating said arm through a righting movement to turn the case from horizontal to upright position and deposit it on a support, a load-retaining member for engaging the top of the case to prevent the contents from being displaced during said righting movement, a pivoted arm for supporting said retaining member, and means for actuating said arm to cause said member to follow said case during approximately one-half of said righting movement and then returning said retaining member to its initial position during the remainder of said movement.

16. A machine as set forth in claim 6 wherein the means on the reciprocating carriage for advancing the opened case from the end of the compact group to the flap-folding station comprises two gripping devices mounted upon said carriage each of said devices having a pair of relatively movable jaws for engaging two of the case flaps, and operating mechanism for said jaws including a pivoted lever operatively connected with said jaws to simultaneously open and close them, a stationary rail mounted adjacent the path of said reciprocating carriage, said actuating lever having a roller projecting from one side thereof to engage said rail, said roller moving along one surface of said rail during the forward movement of the reciprocating carriage to thereby maintain said gripping jaws closed, the opening of the jaws occurring when the roller passes the end of the rail, and means adjacent the end of said rail for moving said lever downwardly and causing said roller to engage the opposite surface of the rail as the carriage commences its backward stroke.

17. In a machine of the class described, a magazine containing a compact horizontal stock of collapsed shipping case blanks supported in edgewise position with their flaps extending horizontally, mechanism for squaring-out the foremost blank of said stack including a vacuum arm disposed at each side of said stack carrying a vacuum cup at its end, flap-retaining devices comprising pairs of fingers disposed one pair on each side of said stack and hollow case-opening arms disposed one at each side of each stack, each of said vacuum arms having horizontal and vertical pivots, the latter being approximately in line with the flap hinge lines when the arms are in flap-engaging position, mechanism for swinging said arms simultaneously about their horizontal pivots to bring said vacuum cups into engagement with the respective flaps at the opposite ends of the foremost blank, mechanism for simultaneously turning said arms about their vertical pivots to open said flaps, upper and lower axially aligned shafts arranged one pair on each side of said stack parallel with the face of the foremost blank,

said shafts carrying said flap-retaining fingers, mechanism for simultaneously rocking said lower shafts to cause said fingers thereon to release their flaps prior to the said vertical turning movement of said vacuum arms, 5 axially slid able rack members within said respective hollow case-opening arms, case-opening members carried by said arms and operatively connected with said rack members to swing from a retracted position to a case-engaging position at right angles to said arms by the axial movement of said rack members, means for simultaneously actuating said rack members to cause said opening members to swing case-engaging position after the release of said lower flaps by said lower fingers and after the opening thereof by the turning movement of 10 said vacuum arms, said lower shaft operating mechanism returning said lower-retaining fingers into contact with the case flaps beneath said outwardly turned flaps so as to hold the case blank against said stack during the opening movement of the case blank, operating mechanism for 15 said upper shafts to cause said upper case-retaining fingers to release the case for opening movement, the horizontal pivots for said case-opening arms being approximately in alignment with one of the folded edges of the foremost case blank, and means for simultaneously 20 actuating said hollow arms to swing about said pivots to open the case.

18. A machine as set forth in claim 17 having devices for gripping the lower opposite flaps of said opened case blank, and mechanism for moving said gripping devices in a direction away from the end of said stack so as to remove the opened case therefrom.

19. In a machine of the class described, a magazine containing collapsed shipping case blanks supported in edgewise position in a compact group, mechanism for 30 squaring-out the foremost blank of said group including a vacuum arm carrying a vacuum cup, double pivot means for said arm comprising a horizontal pivot to allow the arm to swing in a vertical plane into contacting position with the vacuum cup engaging a flap of said case blank, and a vertical pivot whose axis is approximately in line with hinge line of said flap when the arm is swung into contacting position, mechanism for swinging said arm first about its horizontal pivot and then turning said arm about its vertical pivot to open the flap to an acute angle with respect to the plane of said case blank, said vertical pivot when the arm is swung into contacting position being substantially in the plane of said foremost blank.

20. A machine as set forth in claim 19, wherein each 50 of the pivots includes a shaft and bearing therefor, the shaft for the horizontal pivot being hollow, and the bearing for the vertical pivot being mounted on such hollow shaft, a pinion fixed to the vertical pivot shaft, and a rack member axially slid able within said hollow shaft to turn said vacuum arm about its vertical pivot, said rack having arcuate teeth engaging the teeth of said pinion so as to prevent the swinging movement of said vacuum arm about its horizontal pivot from causing disengagement of said rack and pinion teeth.

21. In a machine of the class described, a magazine containing collapsed shipping case blanks supported in edgewise position in a compact group, mechanism for squaring-out the foremost blank of said group including flap-retaining devices comprising pairs of fingers disposed 60 one pair on each side of the group of collapsed case blanks, a pair of axially aligned shafts arranged one pair on each side of said group parallel with the face of the foremost blank, each of said shafts carrying one of said fingers, and means for rocking said shafts approximately simultaneously in opposite directions so as to cause said fingers alternately to release and to hold said flaps.

22. In a machine of the class described, a magazine containing collapsed shipping case blanks supported in edgewise position in a compact group, mechanism for squaring-out the foremost blank of said group including

flap-retaining devices comprising pairs of fingers disposed one pair on each side of the group of collapsed case blanks, a pair of partially telescoped shafts arranged one pair on each side of said group parallel with the face of the foremost blank, one of said fingers being fixed upon the exposed portion of said inner shaft and the other finger of each pair being secured to said outer shaft, and means for rocking said shafts approximately simultaneously in opposite directions so as to cause said fingers alternately to release and to hold said flaps.

23. In a machine of the class described, a magazine containing collapsed shipping case blanks supported in edgewise position in a compact group, mechanism for squaring-out the foremost blank of said group including case-opening mechanism comprising a hollow arm having a rack member axially slidable therein, a case-opening member adapted to swing from a retracted position approximately in alignment with said arm to a case-engaging position substantially at right angles to said arm, said member having a supporting shaft mounted for rocking movement in a bearing carried by said arm near its said outer end, a pinion fixed to said shaft with its teeth engaging the teeth of said rack member, a rock shaft for supporting said hollow arm arranged with its axis approximately in alignment with one of the folded edges of the foremost case blank, means for oscillating said rock shaft to open said case blank, means for axially shifting said rack member substantially at each end of said oscillation to actuate said case-opening member from retracted to case-engaging position and vice-versa.

24. In a machine of the class described, a magazine containing collapsed shipping case blanks supported in edgewise position in a compact group with their flaps extending horizontally, mechanism for squaring-out the foremost case blank of said group, said magazine including mechanism for feeding the case blanks forward to said squaring-out mechanism comprising a slideway for supporting said edgewise blanks, lower and upper feed members for engaging respectively the lower rear portion and the upper rear portion of said group of blanks, lower and upper feed mechanisms for actuating said respective feed members, operating means for said feed mechanisms, each of said mechanisms having a control device for connecting it to said operating means, lower and upper feeler members coacting with the lower and upper face portions of said foremost blank, and means operatively connecting each of said feeler members with the control mechanism of its corresponding feed mechanism.

25. In a machine of the class described, a magazine containing collapsed shipping case blanks supported in edgewise position in a compact group with their flaps extending horizontally, mechanism for squaring-out the foremost case blank of said group, said magazine including mechanism for feeding the case blanks forward to said squaring-out mechanism comprising a slideway for supporting said edgewise blanks, lower and upper feed members for engaging respectively the lower rear portion and the upper rear portion of said group of blanks, lower and upper feed mechanisms for actuating said respective feed members, operating means for said feed mechanisms, each of said mechanisms having a control device for connecting it to said operating means, lower and upper feeler members coacting with the lower and upper face portions of said foremost blank, means operatively connecting each of said feeler members with the control mechanism of its corresponding feed mechanism, and means for interconnecting the control mechanisms of said lower and upper feed mechanisms so that both of said feed members will be advanced by the actuation of either of said feeler members.

26. A machine as set forth in claim 24 wherein said lower and upper feed members are mounted on carriages each slidably supported on a stationary bar arranged lengthwise of the magazine, the lower and upper feed mechanisms each comprising a stationary and a movable

rack carried by said respective supporting bars, means for reciprocating said movable rack, said means including a continuously reciprocating driving dog, and means controlled by one of the feeler members for raising or lowering said driving dog into or out of actuating engagement with said movable rack, and each of said carriages having a pair of pivoted spring-pressed ratchets coacting respectively with said stationary and movable racks to cause the carriage to advance at each reciprocation of said movable rack.

27. A machine as set forth in claim 26 including means for interconnecting the driving dogs of the upper and lower feed mechanisms so that both of said dogs are moved into driving position by movement of either of said feeler members.

28. A machine as set forth in claim 26 having manually-operated means on each of said carriages for releasing the pivoted ratchets thereof from their respective racks so as to permit said carriages to be reset for replenishing of the magazine.

29. A machine as set forth in claim 28 wherein each of said carriages is provided with at least one feed member pivoted thereto and manually-operated means for moving said feed member out of the path of movement of the shipping case blanks and for simultaneously releasing both of said ratchets.

30. A machine as set forth in claim 6 wherein the mechanism at the flap-folding station comprises a pair of flap tuckers and means for actuating said tuckers to fold the two inner bottom flaps inwardly, and mechanism operating to lift slightly the outer bottom flap at the top side of the case prior to the actuation of said flap tuckers so as to insure that said outer flap clears the path of the top edges of the two inner flaps.

31. A machine as set forth in claim 30 wherein mechanism is provided at the flap-folding station for swinging downwardly the previously lifted outer flap.

32. A machine as set forth in claim 6 wherein the packing mechanism includes a funnel through which the charge is inserted in the case, and the mechanism at the packing station comprises a pusher arranged to operate on the bottom of the case and mechanism for operating said pusher to move the mouth of the case onto the funnel of the packing mechanism.

33. A machine as set forth in claim 6 wherein the packing mechanism includes a funnel through which the charge is inserted in the case, the mechanism at the packing station includes a case push-off device arranged to engage the outer flap located at the lower side of the case, and mechanism for actuating said push-off device to cause it to engage the horizontal edge of said flap and push the filled case from the funnel.

34. A machine as set forth in claim 6 wherein the mechanism at the case righting station comprises a case drop-off arm for receiving the case resting on its side, mechanism for actuating said arm through a righting movement to turn the case from horizontal to upright position and deposit it on a support, a load-retaining member for engaging the top of the case to prevent the contents from being displaced during said righting movement, a pivoted arm for supporting said retaining member, and means for actuating said arm to cause said member to follow said case during approximately one-half of said righting movement and then returning said retaining member to its initial position during the remainder of said movement.

35. A machine as set forth in claim 6 wherein the means on the reciprocating carriage for advancing the opened case from the end of the compact group to the flap-folding station comprises two gripping devices mounted upon said carriage each of said devices having a pair of relatively movable jaws for engaging two of the case flaps, means for closing said jaws near the commencement of the forward stroke of the reciprocating

carriage, and mechanism for opening said jaws near the commencement of the rear stroke of the carriage.

36. In a machine of the class described, a magazine containing collapsed shipping case blanks supported in edgewise position in a compact group, mechanism for squaring-out the foremost blank of said group including flap-retaining devices comprising at least one pair of fingers disposed on one side of the group of collapsed case blanks, a pair of axially aligned shafts arranged on said side of said group parallel with the face of the foremost blank, each of said shafts carrying one of said

5
32
fingers, and means for rocking said shafts approximately simultaneously in opposite directions so as to cause said fingers alternately to release and to hold said flaps.
